UNITED STATES PATENT OFFICE

ALBERT J. GURNEY, OF CANTON, OHIO, ASSIGNOR TO THE AMERICAN MINE DOOR CO.,
OF CANTON, OHIO, A CORPORATION OF OHIO

MINE DOOR

Original application filed May 13, 1925, Serial No. 30,078. Divided and this application filed January 20, 1927. Serial No. 162,388.

This invention relates to an improved mine door, being a division of my co-pending application for automatic mine door, filed May 13, 1925, Serial No. 30,078.

5 The invention seeks, among other objects, to provide an improved door structure where in the door wings employed will be supported and braced in a novel manner.

A further object of the invention is to provide a novel mounting for the wings.

And the invention seeks, as a still further object, to provide a door wherein the wings may be readily installed or removed.

Other objects of the invention not specifically mentioned in the foregoing will appear during the course of the following description.

In the drawings:

Figure 1 is an elevation of my improved mine door,

20 Figure 2 is a horizontal section on the line 2—2 of Figure 1, looking in the direction indicated by the arrows,

Figure 3 is a plan view showing a typical bottom hub plate of the wings of the door,

25 Figure 4 is a fragmentary elevation showing one of the bottom hub plates,

Figure 5 is a detail sectional view showing a typical bottom socket plate, and

30 Figure 6 is a detail sectional view showing one of the pintles of the door wings.

In carrying the invention into effect, I employ a door frame including a sill 10, side posts 11, and a cap 12 rigidly secured together. The frame is, as shown in Figure 2, erected diagonally of the mine track, which

35 track is indicated conventionally at 13, and at opposite sides of the frame are provided bumpers 14. Bolted to the door frame in the angles at the lower corners thereof are bottom bearing plates 15 having sockets 16, and bolted to the frame in the angles at the upper corners thereof are top bearing plates 17 having sockets 18 alining with the sockets 16 of the bottom plates.

40 Journaled upon said plates are mating door wings 19 overlapping at their outer vertical margins. Overlying the inner vertical margins of the wings 19 at corresponding sides thereof, are longitudinally extending Z-shaped bars 20,

the oppositely directed flanges of which are indicated at 21 and 22, and overlying said margins of the wings at opposite corresponding sides thereof are longitudinally extending angle bars 23 connected with the bars 20 by rivets or other fastening devices clamping the inner margins of the wings between said bars, the flange 22 of the bars 20 providing stops for the bars 23. Fixed to the flanges 21 of the bars 20 as well as to the wings are 55 outstanding vertically spaced brackets 24 and adjustable through the outer ends of said brackets are brace rods 25. At their forward ends, these rods are equipped with claws 26. Adjustable through corresponding outstanding flanges of the angle bars 23 are brace rods 27 equipped at their forward ends with claws 28 disposed opposite the claws 26, and extending through the claws and through the wings 19 are bolts 29 clamping the claws 60 in engagement with the wings. The claws will thus rigidly anchor the rods 25 and 27 at their forward ends, and screwed on said rods at their rear ends are nuts 30 which may be adjusted for tensioning said rods.

65 Fixed to the lower ends of the bars 20 and 23 are lower hub plates 31, one of which is shown in detail in Figures 3 and 4 of the drawings, and fixed to the upper ends of said bars are upper hub plates 32, one of which is 70 shown in Figure 6. These hub plates are identical with the exception that the lower hub plates are provided with long arms 33 and angularly disposed short arms 34. Formed on the plates are axially disposed hub 75 sockets or sleeves 35 from which extend as particularly shown in Figure 3, flanges 36 and 37. Rising from the plates in spaced relation to the ends of the flanges 36 are flanges 38 while flanges 39 are provided in spaced relation to the flanges 37. Flanges 40 are 80 also provided at right angles to the flanges 39. As best shown in dotted lines in Figure 3, the ends of the Z-shaped bars 20 fit between the flanges 36, 37, 38, 39 and 40 of the hub plates 85 while the ends of the angle bars 23 fit the flanges 36 and 37 of said plates, and extending through the several flanges and through the bars are rivets or other suitable fastening 90 95 100

devices rigidly connecting the hub plates with the bars.

Slidable in the sockets 35 of the hub plates 31 and 32, as best seen in Figure 6, are pintles 41 and adjustable through the inner ends of said sockets to coact with the pintles are set bolts 42 carrying lock nuts 43. The sockets are provided with longitudinally extending slots 44 and extending freely through said slots are angle shaped keys 45 screwed into the pintles, the pintles being provided at longitudinally spaced points with threaded sockets 46 to accommodate said keys. Initially, the keys 45 are engaged in the sockets 46 nearest the outer ends of the pintles, when the set bolts are backed out of the sockets 35 so that the pintles may shift into said sockets. The wings 19 of the door may then be freely disposed in position within the door frame, when the keys of the pintles may be grasped for manually projecting the pintles into the sockets 16 and 18 of the bearing plates 15 and 17. The set bolts 42 are then adjusted to abut the inner ends of the pintles for maintaining the pintles projected and, as will be appreciated, by properly adjusting said bolts the wings may be either elevated or lowered within the door frame. Finally, the keys 45 are removed from the outermost of the sockets 46 of the pintles and, as shown in Figure 6, engaged in the innermost of said sockets to coact with the inner end walls of the slots 44 so that should the bolts 42 become loosened for any reason, the keys will limit the pintles against retraction. Furthermore, as will be seen, the keys will lock the pintles against rotation so that the pintles will turn in the sockets 16 and 18 of the bearing plates to support the door wings for free swinging movement.

As shown in Figure 4, the arms 33 of the lower hub plates 31 are offset downwardly, and extending between the free ends of said arms beneath the rails of the mine track, as shown in Figure 2, is a connecting rod 47 coupling the wings 19 to simultaneously swing in opposite directions. Screwed over the ends of said rod are yokes 48 pivotally connected to the arms, and these yokes are adjustable upon the rod for varying the effective length thereof, the sleeves of the yokes being provided with ears to receive bolts 49 clamping the yokes in adjusted position. Fitting opposite corresponding corners of the posts 11 of the door frame, at the lower ends of said posts, are angle shaped brackets 50 fixed to said posts. As shown in Figure 5, the lower ends of the brackets are received between the posts and the bearing plates 15 to be secured by the same bolts anchoring said plates, and projecting from the brackets are spaced arms 51. Swingingly mounted upon the brackets are levers 52 provided medially with hubs 53 which are freely received between the arms 51 of the

brackets and extending through said arms and through the hubs are pivot pins 54. As shown in Figure 2, the outer ends of the levers are curved toward the posts 11 while the inner ends of the levers extend at opposite sides of the door and, as brought out in Figure 1, are offset with respect to the outer ends of the levers to lie in a plane with the arms 34 of the lower hub plates 31. In this connection it is to be observed, as shown in Figure 2, that the short arm of the lower hub plate seen at the left in Figure 2, stands at approximately a right angle to the long arm of said plate to project at one side of the door, while the short arm of the lower hub plate seen at the right, extends at a greater angle with respect to the long arm of the latter plate to project at the opposite side of the door. Connecting the inner ends of the levers 52 with the free ends of the arms 34 of said hub plates are links 55.

In the closed position of the wings 19, as shown in Figure 2, the inner ends of the levers 52 stand substantially parallel to the arms 34 of the bottom hub plates 31 and, as will now be seen, when the levers are swung so that the inner ends thereof travel toward the wings, the wings will be swung in opposite directions to open position. As the wings are thus swung open, the links and levers are swung toward an aligned position so that when the wings are full open, the links and levers occupy a relation close to dead center. Thus, a portion of the thrust of the wings tending to swing closed will be counteracted by the approximate dead center relation of the links and levers so that the wings may be readily held open while strain upon the operating mechanism connected with the levers will be relieved. Furthermore, the speed of the opening travel of the wings will, as will be seen, be gradually reduced as the wings approach the end of their opening travel so that banging of the wings against the bumpers 14 will be prevented. Connected to the outer ends of the levers 52 are rods 56 operable for swinging the levers and opening the door wings, and associated with said lever are springs 57 for closing the wings.

Having thus described the invention, what I claim is:

1. In a mine door, a door wing, a Z-shaped bar overlying one side of the wing at the inner vertical margin thereof, an angle shaped bar overlying the opposite side of the wing at its inner vertical margin, means connecting the bars with the wing, hub plates having flanges receiving the ends of said bars therebetween and arranged to abut the angularly disposed portions of both of said bars, means extending through the bars and said flanges connecting the hub plates with the bars, and means carried by the hub plates pivotally mounting the wing.

2. In a mine door, a door wing, a Z-shaped bar overlying one side of the wing at its inner vertical margin, an angle shaped bar overlying the opposite side of the wing at said margin thereof, means connecting the bars with the wing, hub plates fixed to the ends of said bars and provided with means pivotally mounting the wing, brackets fixed to one of the angularly disposed portions of said Z-shaped bar, brace rods at one side of the wing engaged with said brackets, and brace rods at the opposite side of the wing engaged with said angle bar.

3. In a mine door, a door wing, longitudinal reinforcing bars fixed to opposite sides of the wing at the inner vertical margin thereof, hub plates having flanges snugly receiving the end portions of the bars therebetween, said bars having angularly disposed portions and said flanges being arranged to abut the angularly disposed portions of both of said bars, means engaged with said flanges connecting the hub plates with the bars, and means carried by the hub plates pivotally mounting the wing.

4. In a mine door, a door wing, reinforcing means for the wing at the inner vertical margin thereof at opposite sides of the wing, claws engaged with the wing at one side thereof, brace rods extending between said claws and through said reinforcing means, claws engaged with the wing at the opposite side thereof, brackets fixed to said reinforcing means at the latter side of the wing, and brace rods extending between the latter claws and said brackets.

5. In a mine door, a door wing, longitudinal reinforcing means disposed at opposite sides of the wing at the inner vertical margin thereof, said reinforcing means having angularly disposed portions, hub plates having upstanding flanges snugly receiving the ends of said reinforcing means therebetween, said flanges being arranged to abut the angularly disposed portions of both of said means, and means carried by said hub plates for swingingly mounting the wing.

In testimony whereof I affix my signature.

ALBERT J. GURNEY.
